(57) **CLAIM**

The ornamental design for an audio video display cabinet, as shown and described.

DESCRIPTION

FIG. 1 is a front view my new design with mildly sloped end profiles;

FIG. 2 is a rear view of FIG. 1;

FIG. 3 an end view of FIG. 1;

FIG. 4 is a top view of FIG. 1;

FIG. 5 is a perspective view of FIG. 1;

FIG. 6 is a front view of a second embodiment of my new design with straight end profiles;

FIG. 7 is a rear view of FIG. 6;

FIG. 8 is an end view of FIG. 6;

FIG. 9 is a top view of FIG. 6; and,

FIG. 10 is a perspective view of FIG. 1 in an open position, it being understood that the broken lines are not a part of the claimed design.

This design features a low profile cabinet proportional to a coffee table with hinged top sections. The body is sloped from rear to front in keeping with the angled shelves that permit improved viewing of audio video components.
